UNITED STATES PATENT OFFICE.

SAMUEL TACKLER, OF NEW YORK, N. Y.

DESIGN FOR A SNAP BUTTON.

Application filed May 26, 1922. Serial No. 2,428. Term of patent 3½ years.

To all whom it may concern:

Be it known that I, SAMUEL TACKLER, a citizen of the United States, and residing at New York, in the county of Bronx and State of New York, have invented a new, original, and ornamental Design for Snap Buttons, of which the following is a specification, reference being had to the accompanying drawing, forming part thereof.

Fig. 1 is a top plan view of a snap button showing my new design;

Fig. 2 a bottom plan view thereof; and
Fig. 3 an edge or side view of the same.

I claim:

The ornamental design for a snap button, as shown.

SAMUEL TACKLER.
